UNITED STATES PATENT OFFICE

WILLIAM THOMAS BUCKINGHAM ROBERTS, OF LEICESTER, ENGLAND, ASSIGNOR TO UNITED SHOE MACHINERY CORPORATION, OF PATERSON, NEW JERSEY, A CORPORATION OF NEW JERSEY

PULLING-OVER MACHINE

Application filed December 28, 1928, Serial No. 329,011, and in Great Britain January 5, 1928.

This invention relates to machines for pulling uppers over lasts, and has more particular relation to the operation and control in such machines of means for gripping and pulling the upper. In one important aspect, it is an object of the invention to provide improvements in a machine of the general type disclosed in Letters Patent No. 1,656,365, granted on January 17, 1928, upon an application of Robert H. Sylvester and Arthur Bates, comprising in its organization a plurality of grippers for pulling an upper respectively in different locations at the same side of the last and means for operating the different grippers independently of each other in respect to the forces applied in pulling the upper, or with controllably different pulling forces, and the invention is accordingly herein illustrated in its application to a machine of that type. It is to be understood, however, that in its more general aspects the invention is not thus limited in its applicability.

An important feature of the invention resides in a novel organization including means for limiting the independence of operation of different independently operated grippers, or relative movement between different grippers in the direction of their pull on the upper, in the upper-pulling operation. In its application to an organization such as disclosed in the above-mentioned Letters Patent, the invention, in one of its aspects, thus provides means whereby adjacent side grippers, operated independently of each other in respect to the forces applied in pulling the upper, may be so controlled as to lose that independence prior to the completion of the upper-pulling operation. For the purpose in view the construction herein shown comprises means for limiting such relative movement between the grippers in the direction of their pull on the upper as may occur, for example, in response to differences in resistance of different portions of the upper to the force of the pull, and thereby rendering the grippers operative conjointly instead of independently in the latter portion of the upper-pulling operation. In the organization illustrated the different adjacent

side grippers are operated respectively by separate updraw levers and springs, and means is provided for rendering either lever effective to limit upper-pulling movement of the other lever relatively thereto. In consequence of such control the operating force applied to one lever is rendered effective also on the other lever by the action of the limiting means. Preferably, as shown, the limiting means is adjustable to vary the amount of permissible relative movement between the different grippers, and by such adjustment the relative movement of the grippers, or their independence of operation, may, if desired, be entirely eliminated. There is thus provided an organization whereby the forces applied to different portions of the upper by different grippers, for example to the portion of the upper in the vicinity of the tip line and the portion at the rear thereof, may be most effectively controlled in accordance with the requirements of a particular line of shoes, and whereby the advantages of independent control of the forces applied in pulling different portions of the upper are availed of without danger of too severe a strain on one portion of the upper as compared with the strain applied to another portion.

In accordance with another feature of the invention there is provided a novel construction and arrangement of side grippers for pulling an upper at the same side of a last, such that while the grippers are operative independently of each other to pull the upper heightwise of the last and are relatively movable in the direction of their pull on the upper, they are prevented from moving relatively to each other in directions transverse to the direction of the pull. As herein illustrated the adjacent grippers are provided with a tongue-and-groove connection between them which permits their relative movements heightwise of the last while preventing them from moving relatively to each other in other directions, so that in such movement of the adjacent grippers as may be effected, for example, lengthwise of the last for tip-straightening purposes, they are necessarily moved as a unit.

The invention further provides novel means for effecting relative movement of opposite side grippers manually in a direction heightwise of the last, for example to adjust the upper laterally of the last or to alter the force of the pull on the upper, the construction shown comprising means whereby side grippers independently movable at the same side of the last to pull the upper, as hereinbefore described, may be moved together heightwise of the last relatively to the grippers at the other side by the use of a single controlling member or handle.

A further feature comprises a novel organization including means for rendering a gripper or grippers inoperative to pull an upper and thus to vary the number of grippers utilized in the operation of the machine on the work, to adapt the machine for effective use on a wide range of sizes.

The above and other features of the invention, including also novel means for controlling adjacent side grippers in their return to starting position, will now be more particularly described by reference to the accompanying drawings and thereafter pointed out in the claims.

In the drawings,

Fig. 1 is a view in side elevation of side gripper mechanism in which novel features of the invention are embodied, with parts shown in section;

Fig. 2 is a rear elevation, partly in section on the line II—II of Fig. 1, with parts broken away;

Figs. 3 and 4 are views showing respectively, in separated relation, the different adjacent side grippers at one side of the machine, illustrating particularly the character of the means provided for connecting the two grippers; and

Fig. 5 is a sectional view of a portion of the gripper shown in Fig. 4, illustrating more clearly means whereby the gripper may be rendered inoperative.

The upper-pulling mechanism herein shown as an illustrative embodiment of the invention is, in its general organization, in many respects similar to that shown in Figs. 1, 2 and 3 of the Letters Patent hereinbefore mentioned, but the parts are arranged in the manner required for their embodiment in a pulling-over machine of the so-called inverted type in which the last is positioned bottom downward, as disclosed in Letters Patent No. 1,510,851, granted on October 7, 1924, upon an application of Arthur E. Jerram and Joseph Gouldbourn. It is contemplated that the machine will include, as heretofore, in addition to two side grippers for pulling the upper at each side of the last, a toe gripper for pulling the upper at the toe end of the last, although the side grippers only are herein illustrated. It will be understood that the side gripper mechanism for pulling the upper

at each side of the last is similar to that at the other side, so that a detailed description of that at one side only will be sufficient for an understanding of the construction.

By reference to Figs. 1, 3 and 4, showing the two side grippers for pulling the upper at one side of the last, it will be seen that one of these grippers 10 is arranged to pull the upper substantially in the location of the tip line and that the other gripper 12 is arranged to apply its pull to the upper in a location farther rearwardly on the vamp. The gripper 10 comprises a gripper casing 14 which carries a pair of upper gripping jaws one of which is shown at 16 and has slidably mounted therein a bar 18 connected by a ball-and-socket joint 19 to an updraw lever 20 (Fig. 2), the term "updraw" being used herein in the sense in which it has been commonly used heretofore with reference to the so-called upright pulling-over machine, although it will be understood that in a machine of the inverted type such as herein shown the so-called updraw movement is in reality a movement in a downward and rearward direction. Similarly the gripper 12 comprises a casing 22 carrying gripper jaws 24 and 25 (Fig. 5) and provided with a bar 26 connected by a ball-and-socket joint 27 to an updraw lever 28 (Fig. 2) at one side of and adjacent to the updraw lever 20. It will be understood that each of these grippers is operated and controlled, in respect to the closing of its jaws, in the same general manner as common heretofore in machines of the general type illustrated, as more fully hereinafter described. At the opposite side of the machine there are provided similar side grippers, of which the bars 30 and 32 are seen in Fig. 2, these bars being connected respectively to adjacent updraw levers 34 and 36.

It will be understood with reference to Fig. 1 that all the four side gripper updraw levers are substantially in alignment laterally of the machine and are pivotally mounted upon the same transversely extending shaft 38 on the frame of the machine. All the four levers are operated by a cam 40 through a slide 42, a yoke 44 carried by the slide and shown in section in Fig. 1, and individually adjustable springs 46, herein shown as coil springs, one for each of the updraw levers, in the same general manner as disclosed in Letters Patent No. 1,656,365 hereinbefore mentioned except that in the machine herein shown all the levers and their connected side grippers are operated substantially simultaneously to pull the upper. Only one of the springs 46 is shown, this being the spring for operating the lever 28, but it will be understood that there is a spring similarly controlled by the yoke 44 for operating each of the four side updraw levers. Associated with each of the springs is a member 48 which is threaded in the yoke 44 and is adjustable to vary inde-

pendently the tension of the spring for controlling the force applied to the lever in pulling the upper. It will thus be evident that the several grippers are operated independently of one another in respect to the forces applied in pulling the upper and that in the upper-pulling operation they may move relatively to one another in response to differences in resistance of different portions of the upper to the force of the pull. It will also be understood that through the separately adjustable springs 46 the different grippers may be operated with controllably different pulling forces.

The construction shown is so designed that all the four side gripper updraw levers may be connected to a retarding device through compensating or equalizing mechanism in the same general manner as described in Letters Patent No. 1,656,365. A rock-shaft 50, which corresponds to the rock-shaft 120 of the above-mentioned Letters Patent and is connected to a dash-pot (not shown) in a well-known manner, carries a housing 52 in which there is mounted for sliding and for rocking movement a bar 54 having on its upper end a boss 56. Fixed in one side of the boss 56 is a pin 58 (Fig. 2) connected by a ball-and-socket joint 60 to one end of a link 62 the other end of which is similarly connected to the middle of a short spindle 64 which in turn is connected by ball-and-socket joints 66 and 68 at its opposite ends to the updraw levers 20 and 28 respectively. The boss 56 is similarly connected to the two updraw levers 34 and 36 at the other side of the machine. These equalizing connections provide means whereby the dash-pot is effective upon all the four side updraw levers to retard the movements of the several levers in pulling the upper, while permitting relative movements between the two levers at each side of the machine, as well as between the two pairs of levers at the opposite sides of the machine, in the direction of the pull on the upper, so that the several levers may operate independently of one another in respect to the forces applied to the upper, as hereinbefore described.

For one of the purposes of this invention, there is provided means for limiting relative movement of the side grippers at the same side of the last in the direction of their pull on the upper, as may be desirable in order to avoid undue strain on any portion of the upper. The updraw lever 20 is accordingly provided, close to the cam-operated slide 42, with a small upstanding projection 70 having a laterally projecting lug 72 that overlies the rear end portion of the adjacent updraw lever 28, but is spaced somewhat therefrom, as indicated in Fig. 1, when the machine is in its starting position. Similarly the lever 28 is provided near the lug 72 with a lug 74 which overlies the lever 20 and is

spaced from that lever when the machine is in starting position. By reason of this construction, although the updraw levers 20 and 28 are separate and are separately operated through their respective springs 46 of individually adjustable strength, so as to be capable of relative movement in the upper-pulling operation and of applying controllably different forces in pulling the upper, yet such capacity for relative movement and such independence of operation are limited by the lugs 72 and 74.

Under certain conditions it may be desirable that the extent of permissible relative movement between the updraw levers which operate adjacent side grippers shall be adjustable, and in the construction shown there is accordingly provided in the lug 72 a stop screw 76, and in the lug 74 a similar stop screw 78. It will be seen that the end of each of these stop screws is in position to contact with the adjacent updraw lever after a predetermined amount of movement of the lever which carries it relatively to the other lever in the direction of the pull, so that these screws provide means for varying as desired the amount of permissible relative movement between the adjacent grippers 10 and 12 in pulling the upper. Preferably the arrangement is such that the stop screws may be adjusted to positions in which they permit relative movement of the levers throughout the upper-pulling operation, that is, without any limit to the extent of such relative movement within the normal operation of the grippers, while by another adjustment of the stop screws the two adjacent levers may be rendered incapable of any relative movement, although the pair of levers at each side will still be movable relatively to the pair at the other side in the upper-pulling operation. Between these two limits the screws may be adjusted to provide for any desired amount of relative movement between the adjacent levers. It will be understood that the updraw levers 34 and 36 at the other side of the machine will be provided with adjustable limiting means such as that described with reference to the levers 20 and 28, as indicated in Fig. 2.

It will be evident that when movement of one of the gripper levers relatively to the adjacent lever is stopped in the manner described prior to the completion of the upper-pulling operation, the force applied to the first lever through its operating spring 46 becomes effective also, in a measure, upon the adjacent lever, in addition to the force of the spring that operates the latter, during the remainder of the upper-pulling operation. Not only, therefore, is there provided means for limiting relative movement of different grippers, but also means for increasing the force of the pull of that gripper which en-

counters the greater resistance or which tends to move with the slower speed.

While the lugs 72 and 74 are herein shown as located at the rear ends of the gripper levers, with the stop screws carried thereby, it will be understood that this arrangement is merely illustrative and that various other constructions and arrangements may be provided for the purposes in view. It is further to be understood that while each of the adjacent side gripper levers is herein shown as provided with limiting means, the invention is not restricted to a construction including means for limiting relative movements of the adjacent grippers in opposite directions, since under any given conditions of adjustment and use only one of the adjacent levers will tend to move farther than the other in pulling the upper.

The machine is further provided with means whereby the operator may, if he so desires, move the adjacent side grippers at either side of the shoe simultaneously in the direction of the pull or in the opposite direction by the use of a single controlling member or handle, notwithstanding the fact that the grippers are capable of moving relatively to each other as hereinbefore described. For this purpose the boss 56 is extended upwardly and is provided with a web 80 (Fig. 1), and fast in a transverse slot in this web is a bar 82 extending across the machine from side to side. Secured to each of the opposite ends of the bar 82 is a forwardly extending operating member or handle 84, these members extending at opposite sides of the machine into positions convenient for manipulation by the operator from his working position in front of the machine. The members 84 are adapted to be utilized during the customary pause which occurs in the cycle of operations of the machine after the grippers have pulled the upper and while they are holding it under tension, for the purpose of moving the two side grippers at one or both sides either in the direction of their pull on the upper or in the opposite direction to increase or relax the force of the pull or to shift the forepart of the upper laterally of the last. If, for example, the throat of the vamp is observed not to be properly positioned laterally of the last, the operator seizes one of the members 84, for example the one at the left-hand side of the machine, and pulls it toward him. This pull serves to rock the boss 56 about the axis of its bar 54 and thus to move the left-hand side gripper levers 20 and 28 in such a direction as to relax the tension on the upper at the left-hand side of the machine, with the result that the springs of the updraw levers at the opposite side move the latter in the reverse direction and thus pull the upper toward the right side of the last. Thus the upper is shifted across the last to centralize the throat of the vamp. If the

right-hand member 84 is pulled, the upper is shifted in the opposite direction.

It has been found that pushing upon one member 84 will not normally give the same result as pulling upon the other member, although the two members are rigidly connected to the same transverse bar 82. If, for example, the operator pushes upon the right-hand member he increases the force of the pull of the grippers on that side of the upper. By reason, however, of the binding of the upper on the last under the pull of the grippers at the other side, the upper normally will not shift but will be stretched on the right-hand side, the boss 56 rocking upon the left-hand ball-and-socket joint 60 as a pivot, and the bar 54 being swung rearwardly by the rocking of the housing 52 about the axis of its rock shaft 50. Thus it is possible to use either member 84 not only for throat-straightening purposes but also to give the upper an extra pull, both grippers on one side being, of course, operated jointly or simultaneously by the member 84.

The machine is further provided with a construction and arrangement of adjacent side grippers such that while these grippers are relatively movable in the direction of their pull on the upper or heightwise of the last during their independent operation as hereinbefore described, they are prevented from moving relatively to each other in directions transverse to the direction of the pull and are thus constrained to move as a unit, for example in pulling the upper inwardly over the bottom of the last or in moving lengthwise of the last to straighten the tip. For this purpose the gripper casings 14 and 22, from which emerge the bars 18 and 26 that are connected to the adjacent updraw levers as hereinbefore described, are locked together by such means as to prevent them from moving relatively to each other in direction transverse to the direction of the pull while permitting such relative movement in the direction of the pull or in the opposite direction in the return of the grippers to starting position. This locking means comprises a T-shaped tongue 86 (Fig. 3) on the casing 14 and a corresponding slot 88 (Fig. 4) extending lengthwise of the casing 22 and arranged to receive the tongue 86. The rear side gripper casing 22 is provided at 90 with a guideway extending lengthwise of the casing by which this casing, and consequently both the adjacent side grippers, may be connected to tip straightening means as common heretofore in pulling-over machines of the general type illustrated.

The two gripper casings 14 and 22 connected as above described extend through the usual form of single orifice 92 in the head 93 of the machine, the tapered walls of this orifice acting as wedging means upon beveled faces 94 and 96 of the connected side gripper

casings to centralize the grippers in respect to movement lengthwise of the last in response to their return movement heightwise of the last before the machine stops at the end of the cycle. In order to prevent the relative movement such as hereinbefore described between the casings 14 and 22 in directions heightwise of the last from interfering with the proper centralizing of the two side grippers, lugs 98 and 100 are provided respectively on the casings 14 and 22 for engagement with the head 93 when each of the casings reaches its normal starting position. Accordingly, if one of the gripper casings arrives in its normal position before the other casing, its lug will engage the head 93 and stop it from moving beyond that position, and therefore from being displaced too far laterally by the action of the tapered wall of the orifice 92 before the other casing arrives in its normal position.

It will be understood that otherwise than as above described the two adjacent side gripper casings will be guided and controlled in substantially the same manner as the single gripper casing of the twin side gripper of the well-known Rex type of pulling-over machine or its later inverted form the general character of which is disclosed in the Letters Patent No. 1,510,851. Thus control of adjacent side grippers of such machines in the manner required by the present invention may be provided for with substantially no alterations other than such as hereinbefore set forth.

There is further provided, in the construction shown, means whereby the rearmost side gripper at each side of the machine, i. e., the side gripper that operates farthest from the end of the toe, may, if desired, be rendered inoperative, so that the machine may be used to pull the upper by means of a single gripper at each side in addition to the usual toe gripper, thus adapting the machine to operate, for example, upon very small shoes, in accordance with the general object disclosed in Letters Patent No. 1,543,804, granted on June 30, 1925, upon an application of A. E. Stone. As applied to a machine having the characteristics hereinbefore described, it is desirable that means for thus rendering the rear side grippers inoperative be located on the outer sides of the gripper casings, i. e., the sides that face outwardly from the center of the machine, to render such means conveniently accessible, and accordingly there is provided mechanism of this character which involves also in other respects novel features of construction. For an understanding of this construction, it may be explained that the jaw 25 (Fig. 5) is fast on the gripper casing 22 and that the jaw 24 is pivoted at 102 on the casing for swinging movement toward and from the fixed jaw. Further, in accordance with the usual con-

struction of grippers such as commonly used heretofore, there is provided a jaw-closing slide 104 having thereon a roll 106 for engaging an extension 108 of the jaw 24 to close the jaw, and a latch 110 pivoted at 112 on the end of the gripper bar 26 and arranged to engage a cross-bar 114 on the slide 104 to connect the bar 26 to the slide and thereby render the bar effective to move the slide and close and operate the gripper. The latch 110 is normally pressed by a spring plunger 116 into position to connect it with the cross-bar 114, as illustrated in Fig. 5. There is also provided a tripping member 118 pivoted at 120 on the closing slide 104 and movable to disconnect the latch 110 from the closing slide and cause the opening of the jaws at a predetermined time in the cycle. These various parts are all constructed and operate substantially as heretofore.

In order to render the rear gripper inoperative, there is provided in the construction herein shown means on the outer side of the gripper casing for holding the tripping member 118 in its inner position after it has been moved manually to that position, so as to render the latch 110 ineffective to connect the bar 26 to the closing slide 104 when the bar is operated by its updraw lever. For this purpose there is fast on the member 118 a laterally projecting lug 122, and pivoted at 124 on the outer side of the casing 22 is a catch 126 which is movable from a position in which it is clear of the lug 122 to a position in which a portion of it overlies the lug, the member 118 having first been moved to its inner position. This catch has a longitudinal recess 128 to receive the lug 122, this recess being of such length as to permit a certain amount of movement of the lug with the closing slide 104 lengthwise of the gripper casing 22 while the latch 110 is inoperative, the purpose of this arrangement being hereinafter described.

The catch 126 has an arm 130 (Fig. 4) provided with a small rounded knob 132 which is adapted to enter one or the other or two holes 134 in a spring 136 fixed on the gripper casing 22 in order to hold the catch in either its operative or its inoperative position. If the catch is in its inoperative position, as illustrated in the drawings, the gripper operates normally. If it is in its operative position it overlies the lug 122 and thereby holds the tripping member 118 in its inner position so as to prevent the latch 110 from functioning, the result being that upon the starting of the machine the jaw-closing slide 104 is not operated by the gripper bar 26 and consequently the movable jaw 24 is not closed to grip the upper. It will be understood that as the bar 26 is thus moved idly, the latch is moved with it, but is then maintained in inoperative position by engagement with the left-hand side of the cross-bar 114 (Fig. 5). Of the

two side grippers at each side of the machine only the foremost gripper 10 will, therefore, operate to grip and pull the upper.

In case the rearmost side gripper at each side is rendered inoperative as above described, it may happen that in the inward movement of the side wiping and tacking mechanism with which machines of the general type illustrated are provided, that mechanism will strike the outer face of the open gripper jaw 24, and the construction herein disclosed is such as to avoid objectionable results, for example from undue strain on the grippers, if this should occur. That is, there is provision for partial closing of the jaw in response to such engagement of the wiping and tacking means therewith, without causing the jaw to grip the upper. It will be noted that, in response to pressure applied against the jaw 24 in the manner referred to, its extension 108 by engagement with the hub of the tripping member 118 will cause the closing slide 104 to move to a certain extent lengthwise of the gripper casing, this arrangement permitting movement of the jaw far enough to avoid objectionable consequences from its interference with the side wiping and tacking means but not far enough to grip the upper. Since the member 118 is carried by the closing slide, the recess 128 in the catch 126 is elongated as hereinbefore described to permit the necessary movement of the lug 122 in response to such movement of the slide.

Since the connections of the side gripper bars 18 and 26 to their respective updraw levers 20 and 28 are at different distances from the common pivot 38 of these levers, the tendency is to give these gripper bars movements differing slightly in extent for the same extent of movement of the rear ends of the updraw levers. This would normally result in the closing of the different grippers at slightly different times. To avoid this the extensions 108 of the movable jaws which are engaged by the rolls 106 on the closing slides may be differently shaped to cause the different grippers to close substantially simultaneously.

The manner of operation of the machine has been fully explained in connection with the description of the various features of construction, and accordingly requires no further explanation.

Having described the invention, what I claim as new and desire to secure by Letters Patent of the United States is:—

1. In a machine of the class described, a plurality of grippers for pulling an upper over a last respectively in different locations at the same side of the last, means for operating said grippers independently of each other in respect to the forces applied in pulling the upper, and means for limiting

such independence of operation of the grippers.

2. In a machine of the class described, a plurality of grippers for pulling an upper over a last respectively in different locations at the same side of the last, and means for operating said grippers independently of each other in respect to the forces applied in pulling the upper, or without such independence, in accordance with the positional relation between said grippers resulting from differences in resistance of different portions of the upper to the force of the pull.

3. In a machine of the class described, a plurality of grippers for pulling an upper over a last respectively in different locations at the same side of the last, and automatic power-operated means for operating said grippers at one time in the upper-pulling operation independently of each other in respect to the forces applied in pulling the upper and at another time in that operation without such independence.

4. In a machine of the class described, a plurality of grippers for pulling an upper over a last respectively in different locations at the same side of the last, means for operating each of said grippers with a force determined independently of the force applied to the other, and means to render the force applied to one gripper effective also on the other before the completion of the upper-pulling operation.

5. In a machine of the class described, a plurality of grippers for pulling an upper over a last respectively in different locations at the same side of the last, means for operating each of said grippers with a force determined independently of the force applied to the other, and means dependent for its operation upon relative movement between said grippers in the direction of their pull on the upper to render the force applied to one gripper effective also on the other.

6. In a machine of the class described, a plurality of grippers for pulling an upper over a last respectively in different locations at the same side of the last, means for operating each of said grippers with a force determined independently of the force applied to the other, and means to render the force applied to one gripper effective also on the other at a variable time in the upper-pulling operation depending upon relative movement between the grippers in response to differences in resistance of different portions of the upper to the force of the pull.

7. In a machine of the class described, a plurality of grippers for pulling an upper over a last respectively in different locations at the same side of the last, means for operating said grippers independently of each other in respect to the forces applied in pulling the upper, and adjustable means for

variably limiting such independence of operation of the grippers.

8. In a machine of the class described, a plurality of grippers for pulling an upper over a last respectively in different locations at the same side of the last, means for operating said grippers independently of each other in respect to the forces applied in pulling the upper, and means adjustable to prevent such independence of operation of the grippers.

9. In a machine of the class described, a plurality of grippers for pulling an upper over a last respectively in different locations at the same side of the last, means for operating said grippers independently of each other in respect to the forces applied in pulling the upper, and means dependent for its operation upon a positional relation between said grippers assumed in response to differences in resistance of different portions of the upper to the force of the pull to limit such independence of operation of the grippers, said last-named means being adjustable to vary that positional relation.

10. In a machine of the class described, a plurality of grippers for pulling an upper over a last respectively in different locations at the same side of the last, means for operating each of said grippers with a force determined independently of the force applied to the other, and means dependent for its operation upon relative movement between said grippers in the direction of their pull on the upper to render the force applied to one gripper effective also on the other, said last-named means being adjustable to vary the amount of such relative movement of the grippers.

40 11. In a machine of the class described, a plurality of grippers for pulling an upper over a last respectively in different locations at the same side of the last, means including separate springs for operating the different respective grippers with controllably different forces to pull the upper, and automatic means to render said springs conjoint in their action on one of the grippers before the completion of the upper-pulling operation.

50 12. In a machine of the class described, a plurality of grippers for pulling an upper over a last respectively in different locations at the same side of the last, means including separate springs for operating the different respective grippers with controllably different forces to pull the upper, and means dependent for its operation upon relative movement between said grippers in the direction of their pull on the upper to render said springs conjoint in their action upon one of the grippers.

60 13. In a machine of the class described, a plurality of grippers for pulling an upper over a last respectively in different locations at the same side of the last, means including

separate springs for operating the different respective grippers with controllably different forces to pull the upper, and means dependent for its operation upon relative movement between said grippers in the direction of their pull on the upper to render said springs conjoint in their action upon one of the grippers, said last-named means being adjustable to vary the amount of relative movement between the grippers before the springs begin to act conjointly.

70 14. In a machine of the class described, a plurality of grippers for pulling an upper over a last respectively in different locations at the same side of the last, means including separate springs for operating the different respective grippers to pull the upper, and means constructed to render the spring for operating one of the grippers effective also on the other gripper after the beginning of the upper-pulling operation of both grippers.

80 15. In a machine of the class described, a plurality of grippers for pulling an upper over a last respectively in different locations at the same side of the last, means including separate springs for operating the different respective grippers to pull the upper, and means constructed to render the spring for operating one of the grippers effective also on the other gripper at a variable time in the upper-pulling operation depending upon differences in resistance encountered by the different grippers in pulling the upper.

90 16. In a machine of the class described, a plurality of grippers for pulling an upper over a last, means for operating said grippers independently of each other in respect to the forces applied in pulling the upper with provision for relative movement between them in the direction of their pull in response to differences in resistance of different portions of the upper to the force of the pull, and automatic means for limiting such relative movement.

100 17. In a machine of the class described, a plurality of grippers for pulling an upper over a last, means including separate springs for operating the different respective grippers with controllably different forces to pull the upper, and means constructed to render the force applied to one gripper effective also on the other prior to the completion of the upper-pulling operation.

110 18. In a machine of the class described, a plurality of grippers for pulling an upper over a last, means including separate springs for operating the different respective grippers with controllably different forces to pull the upper with provision for relative movement between said grippers in the direction of their pull on the upper, and means for limiting such relative movement.

120 19. In a machine of the class described, a plurality of grippers for pulling an upper over a last, means including separate springs

for operating the different respective grippers with provision for relative movement between said grippers in the direction of the pull in response to differences in resistance of different portions of the upper to the force of the pull, and automatic means for limiting such relative movement and for rendering the force applied to one gripper effective also on the other prior to the completion of 10 the upper-pulling operation.

20. In a machine of the class described, a plurality of grippers for pulling an upper over a last, means for operating said grippers to pull the upper with provision for relative movement between them in the direction of the pull in response to differences in resistance of different portions of the upper to the force of the pull, and means adjustable to prevent such relative movement.

21. In a machine of the class described, a plurality of grippers for pulling an upper over a last respectively in different locations at the same side of the last, means for operating said grippers to pull the upper with provision for relative movement between them in the direction of their pull in response to differences in resistance of different portions of the upper to the force of the pull while they are both pulling the upper, and means 25 for limiting said relative movement.

22. In a machine of the class described, a plurality of grippers for pulling an upper over a last respectively in different locations at the same side of the last, means for operating said grippers to pull the upper with provision for movement of either gripper relatively to the other in the direction of the pull while they are both pulling the upper, and means for limiting such movement of 30 either gripper relatively to the other in pulling the upper.

23. In a machine of the class described, a plurality of grippers for pulling an upper over a last respectively in different locations at the same side of the last, means for operating said grippers to pull the upper with provision for relative movement between them in the direction of their pull in accordance with differences in resistance of different 45 portions of the upper to the force of the pull while they are both pulling the upper, and adjustable means for variably limiting said relative movement.

24. In a machine of the class described, a plurality of grippers for pulling an upper over a last respectively in different locations at the same side of the last, means for operating said grippers independently of each other in respect to the forces applied in pulling 55 the upper while permitting them to move relatively to each other in response to differences in resistance of different portions of the upper to the force of the pull, and means for limiting such relative movement of the 60 grippers.

25. In a machine of the class described, a plurality of grippers for pulling an upper over a last respectively in different locations at the same side of the last, means comprising separate levers for operating the different respective grippers to pull the upper with provision for relative movement between the different levers in the upper-pulling operation, and means for limiting such relative movement of the levers.

26. In a machine of the class described, a plurality of grippers for pulling an upper over a last respectively in different locations at the same side of the last, means comprising separate levers for operating the different respective grippers to pull the upper with provision for relative movement between the different levers in the upper-pulling operation, and means for rendering one of said levers effective to limit movement of the other 75 lever relatively thereto in pulling the upper.

27. In a machine of the class described, a plurality of grippers for pulling an upper over a last respectively in different locations at the same side of the last, means comprising separate levers for operating the different respective grippers to pull the upper with provision for relative movement between the different levers in the upper-pulling operation, and means for rendering each of said 80 levers effective to limit movement of the other lever relatively thereto in pulling the upper.

28. In a machine of the class described, a plurality of grippers for pulling an upper over a last respectively in different locations at the same side of the last, means comprising separate levers for operating the different respective grippers to pull the upper with provision for relative movement between the different levers in the upper-pulling operation, and adjustable means for variably limiting 85 such relative movement of the levers.

29. In a machine of the class described, a plurality of grippers for pulling an upper over a last respectively in different locations at the same side of the last, means comprising separate levers for operating the different respective grippers to pull the upper with provision for relative movement between the different levers in the upper-pulling operation, and means adjustable at the will of the operator to prevent such relative movement of the levers.

30. In a machine of the class described, a plurality of grippers for pulling an upper over a last respectively in different locations at the same side of the last, and means comprising separate levers for operating the different respective grippers to pull the upper with provision for relative movement between the different levers in the upper-pulling operation, each of said levers having an adjustable stop thereon arranged to co-operate with the other lever to limit variably the relative movement of the levers.

31. In a machine of the class described, a plurality of grippers for pulling an upper over a last respectively in different locations at the same side of the last, separate levers for operating the different respective grippers, and means for operating said levers independently of each other at one time in the upper-pulling operation and as a unit at another time in said operation. 5
- 10 32. In a machine of the class described, a plurality of grippers for pulling an upper over a last respectively in different locations at the same side of the last, separate levers for operating the different respective grippers, and adjustable means for operating said levers either independently or as a unit in pulling the upper. 15
- 20 33. In a machine of the class described, a plurality of grippers for pulling an upper over a last respectively in different locations at the same side of the last, means for operating said grippers independently of each other to pull the upper comprising a separate lever and operating means therefor connected to each gripper, and means for rendering one of said levers effective to apply operating force to the other lever prior to the completion of the upper-pulling operation. 25
- 30 34. In a machine of the class described, a plurality of grippers for pulling an upper over a last respectively in different locations at the same side of the last, means for operating said grippers independently of each other to pull the upper comprising a separate lever and operating means therefor connected to each gripper, and means dependent for its operation upon relative movement between said levers in the pulling of the upper to cause one lever to apply operating force to the other lever. 35
- 40 35. In a machine of the class described, a plurality of grippers for pulling an upper over a last respectively in different locations at the same side of the last, separate levers for operating the different respective grippers with provision for relative movement between said levers in response to differences in resistance of different portions of the upper to the force of the pull, separate springs for applying controllably different operating forces to the different levers, and means for limiting the relative movement between said levers in the pulling of the upper. 45
- 50 36. In a machine of the class described, a plurality of grippers for pulling an upper over a last respectively in different locations at the same side of the last, separate levers for operating the different respective grippers with provision for relative movement between said levers in response to differences in resistance of different portions of the upper to the force of the pull, separate springs for applying controllably different operating forces to the different levers, and adjustable 55
- 60 means for variably limiting the movement of either lever relatively to the other in the pulling of the upper. 65
- 70 37. In a machine of the class described, a plurality of grippers for pulling an upper over a last, means comprising separate levers for operating the different respective grippers to pull the upper with provision for relative movement between the different levers in the upper-pulling operation, and automatic means for limiting such relative movement of the levers. 75
- 80 38. In a machine of the class described, a plurality of grippers for pulling an upper over a last, means comprising separate levers for operating the different respective grippers to pull the upper with provision for relative movement between the different levers in the upper-pulling operation in response to differences in resistance of different portions of the upper to the force of the pull, and means to render one of the levers effective as a stop to limit movement of the other lever relatively thereto while both levers continue their upper-pulling movement. 85
- 90 39. In a machine of the class described, a plurality of grippers for pulling an upper over a last, means comprising separate levers for operating the different respective grippers to pull the upper with provision for relative movement between the different levers in the upper-pulling operation in response to differences in resistance of different portions of the upper to the force of the pull, and means adjustable to limit variably such relative movement of the levers. 95
- 100 40. In a machine of the class described, a plurality of grippers for pulling an upper over a last, means comprising separate levers and springs for operating the different respective grippers with controllably different forces to pull the upper with provision for relative movement between the different levers in the upper-pulling operation in response to differences in resistance of different portions of the upper to the force of the pull, and means for limiting such relative movement of the levers and for thereby rendering the operating force applied to one lever effective also on the other lever. 105
- 110 41. In a machine of the class described, a pair of grippers for pulling an upper at the same side of a last, and means for operating said grippers independently of each other to pull the upper heightwise of the last, said grippers being so connected together as to permit them to move relatively to each other in the direction of the heightwise pull on the upper but to prevent relative movement between them in directions transverse to the direction of said pull. 115
- 120 42. In a machine of the class described, a pair of grippers for pulling an upper at the same side of a last, means for operating said grippers independently of each other to pull the upper heightwise of the last, and a 130
- 125

tongue-and-groove connection between said grippers constructed and arranged to permit them to move relatively to each other in the direction of the heightwise pull on the upper while preventing relative movement between them in directions transverse to the direction of said pull.

43. In a machine of the class described, a pair of grippers for pulling an upper at the same side of a last, means comprising separate levers for operating the different respective grippers to pull the upper heightwise of the last, and a connection between said grippers constructed to permit relative movement between them in the direction of the heightwise pull on the upper while preventing relative movement between them in directions transverse to the direction of said pull.

44. In a machine of the class described, a pair of adjacent side grippers mounted for independent movements heightwise of a last both in pulling an upper and in returning to starting position and connected together to move as a unit lengthwise of the last, means arranged to operate on said grippers in response to their return movements heightwise of the last to centralize them in respect to movement lengthwise of the last, and additional means for limiting the return movement of each gripper heightwise of the last independently of the return movement of the other gripper.

45. In a machine of the class described, a pair of adjacent side grippers mounted for independent movements heightwise of a last both in pulling an upper and in returning to starting position and connected together to move as a unit lengthwise of the last, wedging means arranged to act on either gripper independently in response to its return movement heightwise of the last to impart to both grippers return movement lengthwise of the last, and means for limiting the return movement of each gripper heightwise of the last independently of the corresponding movement of the other gripper to prevent an excess movement of the grippers lengthwise of the last by the action of the wedging means.

46. In a machine of the class described, a plurality of grippers for pulling an upper over a last respectively in different locations at each side of the last, means for operating said grippers independently of one another in respect to the forces applied in pulling the upper with provision for relative movement heightwise of the last between the different grippers at each side in the upper-pulling operation, and a manually operated member connected to the different grippers at one side for moving them relatively to the grippers at the other side in a direction heightwise of the last while the upper is held under tension.

47. In a machine of the class described, a plurality of grippers for pulling an upper

over a last respectively in different locations at each side of the last, means for operating said grippers independently of one another in respect to the forces applied in pulling the upper with provision for relative movement heightwise of the last between the different grippers at each side in the upper-pulling operation, a rocking connection between the different grippers at each side of the last constructed to permit such relative movement between them, and a manually operated member at each side of the machine arranged to act through said rocking connection to move the different grippers at that side relatively to the grippers at the other side in a direction heightwise of the last while the upper is held under tension.

48. In a machine of the class described, a plurality of grippers for pulling an upper over a last respectively in different locations at each side of the last, means for operating said grippers independently of one another in respect to the forces applied in pulling the upper with provision for relative movement between the grippers at the opposite sides and between the different grippers at each side in the direction of their pull in the upper-pulling operation, and a manually operated member at each side of the machine arranged to move the different grippers at that side relatively to the grippers at the other side either in the direction of their pull or in the opposite direction.

49. In a machine of the class described, a plurality of grippers for pulling an upper over a last respectively in different locations at each side of the last, means comprising separate updraw levers for operating the different respective grippers with provision for relative movement between the levers at each side in the direction of their pull on the upper in the upper-pulling operation, and a manually operated member connected to the different updraw levers at one side for moving them relatively to the levers at the other side while the upper is held under tension.

50. In a machine of the class described, a plurality of grippers for pulling an upper over a last respectively in different locations at each side of the last, means comprising separate updraw levers for operating the different respective grippers with provision for relative movement between the different levers at each side in the upper-pulling operation, and a manually operated member at each side of the machine connected to the different updraw levers at that side for moving them relatively to the levers at the other side either in the direction of their pull or in the opposite direction.

51. In a machine of the class described, a plurality of grippers for pulling an upper over a last respectively in different locations at each side of the last, means comprising

separate updraw levers for operating the different respective grippers with provision for relative movement between the levers at the opposite sides and between the different levers at each side in the upper-pulling operation, equalizing connections between the levers at the opposite sides and between the different levers at each side constructed to permit the relative movements of the different levers, and a manually operated member at each side of the machine arranged to act through said equalizing connections to move the levers at that side relatively to the levers at the other side either in the direction 15 of their pull or in the opposite direction.

52. In a machine of the class described, a plurality of grippers for pulling an upper over a last respectively in different locations at the same side of the last, means for operating said grippers independently of each other in respect to the forces applied in pulling the upper, and means for rendering one of said grippers inoperative to grip and pull the upper throughout the operation of the 25 machine without preventing the upper-pulling operation of the other gripper.

53. In a machine of the class described, a plurality of grippers for pulling an upper over a last respectively in different locations 30 at the same side of the last, means comprising separate updraw levers for operating the different respective grippers, and means for rendering one of said grippers inoperative to pull the upper during the movement of its updraw lever while the other gripper remains normally operative.

54. In a machine of the class described, a plurality of grippers for pulling an upper over a last respectively in different locations 40 at the same side of the last, each of said grippers comprising jaws relatively movable to grip the upper, means comprising separate updraw levers for operating the different respective grippers to cause their jaws to grip and to pull the upper, and a device adjustable to prevent the closing of the jaws of one of said grippers during the movement of its updraw lever while the other gripper is operated to pull the upper.

55. In a machine of the class described, a plurality of grippers for pulling an upper over a last respectively in different locations at the same side of the last, each of said grippers comprising a gripper casing having jaws thereon relatively movable to grip the upper, means for operating said grippers independently of each other in respect to the forces applied in pulling the upper, and means mounted on the outer side of one of said gripper casings for rendering the jaws of that gripper inoperative to grip the upper throughout the operation of the machine without preventing the upper-pulling operation of the other gripper.

56. In a machine of the class described, a

plurality of grippers for pulling an upper over a last respectively in different locations at the same side of the last, each of said grippers comprising a pair of relatively movable jaws and a gripper bar movable to close said jaws and to operate them to pull the upper, separate updraw levers connected respectively to the different gripper bars, and means for rendering the gripper bar of one of said grippers inoperative to close the jaws during the movement of said bar without preventing the upper-pulling operation of the other gripper.

57. In a machine of the class described, a plurality of grippers for pulling an upper over a last respectively in different locations at the same side of the last, each of said grippers comprising a pair of relatively movable jaws and a latch movable to trip said jaws after the pull to cause them to release the upper, and means for maintaining the latch of one of said grippers in tripping position during the operation of the machine to prevent that gripper from gripping and pulling the upper during the upper-pulling operation of the other gripper.

58. In a machine of the class described, a plurality of grippers for pulling an upper over a last respectively in different locations at the same side of the last, each of said grippers comprising a pair of relatively movable jaws, a gripper bar, a closing slide and a latch for connecting the gripper bar to the closing slide to close and operate the jaws by the movement of said bar, and means for maintaining the latch of one of the grippers in position to disconnect said bar from the closing slide to prevent the gripping and pulling of the upper by that gripper during the upper-pulling operation of the other gripper.

59. In a machine of the class described, a gripper for pulling an upper over a last, said gripper comprising a pair of relatively movable jaws and mechanism including a latch for operating said jaws to grip and pull the upper, and means for maintaining said latch in position to prevent the gripping of the upper by said jaws throughout the operation of the machine.

60. In a machine of the class described, a gripper for pulling an upper over a last, said gripper comprising a pair of relatively movable jaws, mechanism including a latch for operating said jaws to grip and pull the upper, and a member for operating said latch after the pull to cause the jaws to release the upper, and means for maintaining said member in position to prevent the latch from operating and thereby to prevent the gripping of the upper by the jaws during the operation of the machine.

61. In a machine of the class described, a gripper for pulling an upper over a last, said gripper comprising a pair of relatively movable jaws, a gripper bar, a closing slide, and

a latch for connecting the gripper bar to the closing slide to close and operate the jaws by movement of said bar, and means for maintaining said latch in inoperative position to disconnect the bar from the closing slide throughout the operation of the machine.

62. In a machine of the class described, a gripper for pulling an upper over a last, said gripper comprising a gripper casing, a pair of relatively movable jaws on said casing, a gripper bar, a closing slide, and a latch for connecting the gripper bar to the closing slide to close and operate the jaws by movement of said bar, and a device on the exterior of the gripper casing for locking said latch in inoperative position to prevent the bar from operating the closing slide throughout the operation of the machine.

In testimony whereof I have signed my name to this specification.

WILLIAM THOMAS BUCKINGHAM ROBERTS.
